UNITED STATES PATENT OFFICE

105,645

DESIGN FOR AN ACCESSORY DRAWER FOR POWER TABLES

Walter A. Adams, Rochester, N. Y.

Application February 14, 1936, Serial No. 61,179

Term of patent 7 years

To all whom it may concern:

Be it known that I, Walter A. Adams, a citizen of the United States, residing at Rochester, in the county of Monroe and State of New York, have invented a new, original, and ornamental Design for an Accessory Drawer for Power Tables, of which the following is a specification, reference being had to the accompanying drawing, forming part thereof, and in which:

Fig. 1 is a perspective view of the article showing my new design.

Fig. 2 is a front elevation, and,

Fig. 3 is a top plan view.

The characteristic feature of the design resides in the substantially flat member extending longitudinally of the substantially quadrant

shaped drawer and arranged flat against the plane vertical wall of the same and projecting beyond both quadrant shaped end walls of the drawer and having one of the projecting ends curved into approximately semi-circular form and the other end straight, the straight projecting end of the member and an intermediate portion thereof being reduced in width to form recesses and having alined flanges arranged in pairs and projecting from the upper and lower edges of the longitudinal member at said recesses, as shown.

I claim:

The ornamental design for an accessory drawer for power tables, as shown and described.

WALTER A. ADAMS.
